UNITED STATES PATENT OFFICE.

FREDERIC G. NICOLAUS, OF CLEVELAND, OHIO, ASSIGNOR TO AMERICAN STOVE COMPANY, OF ST. LOUIS, MISSOURI, A CORPORATION OF NEW JERSEY.

LIGHTER FOR GAS-STOVES.

1,137,520.

Specification of Letters Patent.

Patented Apr. 27, 1915.

Application filed January 5, 1915. Serial No. 658.

To all whom it may concern:

Be it known that I, FREDERIC G. NICOLAUS, a citizen of the United States, residing at Cleveland, in the county of Cuyahoga and State of Ohio, have invented certain new and useful Improvements in Lighters for Gas-Stoves, of which the following is a specification, reference being had therein to the accompanying drawing.

10 My invention relates to improvements in lighters for gas stoves.

The object of my invention is to provide a lighter located between the four burners of a gas stove and so arranged that the flame from the lighter will travel across to the burners and ignite the same and also providing a pilot-light so arranged that the lighter will instantaneously ignite therefrom.

20 Another object of my invention is to provide a lighter of this character which will produce two flashes during the single operation of the valve, thus if the burners are not ignited from the first flash, they will be 25 by the second flash and thus produce a more effective lighter of this character.

A further object of my invention is to provide a lighter of this character in which the bell carried by the lighter is constructed 30 to supply the proper amount of air to the lighter and at the same time prevent any drippings from the stove from entering the bell and clogging the lighter.

A still further object of my invention is 35 to provide a simple, cheap and effective lighter of this character adapted to be readily applied to the ordinary stove and having certain details of structure and operation hereinafter more fully set forth.

40 In the accompanying drawings—Figure 1 is a perspective view of my improved lighter. Fig. 2 is a bottom plan view partly in section. Fig. 3 is a perspective view of the gas controlling valve, showing the several parts in their dissembled relation. Fig. 4 is a vertical longitudinal sectional view of the lighter shown in Fig. 1. Fig. 5 is a horizontal sectional view of the lighter proper, showing the relative position of the 45 openings in the burner and the bell and the position of the burners in respect thereto. Fig. 6 is a perspective view of the burner tip and bell in their dissembled position.

Referring now to the drawings, 1 represents my improved turning valve, which has

its outer end screw-threaded and adapted to be connected to the gas supply of the stove, as is readily understood by those skilled in the art. The casing of the valve 1 is provided with an off-set portion 3 provided with a tapering opening 4, therethrough and into which fits the turning plug 5 having a transverse curved opening 6, adapted to communicate with the passage 7 leading to the rear of the casing and the passage 8 leading to the forward end of the casing. The plug above the casing is provided with a circular housing 9, in which is arranged a coiled spring 10, having one end securely fastened to the plug at 11 and the opposite end has a hooked portion 12, adapted to engage the pin 13, carried by the casing and whereby the plug is at all times held in the closed position in Fig. 2 of the drawings. The plug 4, below the lower end of the housing, is screw-threaded and has a coiled spring 14 surrounding the same. The said coiled spring bears against the lower face of the casing and has its opposite end bearing against the nut 15, screwed upon the lower-threaded end of the plug 5. By this structure it will be seen that the spring normally holds the plug 4 in its downward position forming a tight joint with the opening 4 in the casing 2, to prevent the leakage of gas therearound. As heretofore stated, the spring 10 normally holds the plug in the position shown in Fig. 2 and when the plug is turned by means of the handle 16 and the opening 6 allows the gas to pass from the passage 6 to the passage 8 to supply the lighter with gas. When the handle 16 has been turned to the left as far as it will travel, the opening 6 assumes the position shown in dotted lines, Fig. 2, and the spring has been compressed. Upon releasing the handle 16, the spring carries the turning plug 4, back to the position shown in full line Fig. 2, and in its travel allows a certain amount of gas to pass through the passage 6 to the passage 8 for supplying the lighter with gas.

The casing of my improved valve is provided with a straight opening 17 therethrough and the rear end of the passage 7 communicates therewith, as fully shown in Fig. 2 of the drawings. The forward end of the casing is provided with a large internally screw-threaded opening 18 with which communicates the passage 17 and 8, and are screwed into the said opening is the main

gas supply pipe 19 leading upwardly to a point between the four burners of the stove, as will be later described. The valve casing 1 is provided with a screw valve 20, which is 5 adapted to intercept the passage 8 and to regulate the flow of gas to the main supply pipe 19. The passage 17 is provided with a screw valve 21, which is adapted to regulate the flow of gas to the pilot-light pipe 22, 10 fully shown in Fig. 2 of the drawing. It will be seen from the structure herein shown that the passage 17 supplying gas to the pilot-light burner, hereinafter more fully described, through the pipe 22, is at all times 15 in communication with the gas supply and, therefore, the pilot-light is continuously burning. The pipe 19 is curved downwardly at 23 and upwardly at 24, and screw-threaded at 25. Screwed upon the threaded portion 20 is the main lighter burner 26. This burner has a squared portion 27 resting upon a central depressed squared portion 28 in the lower end of the bell 29 and is locked therein by means of the nut 30, screwed 25 upon the threaded extension 31 of the main burner 26. The main burner is provided with four openings 32, arranged opposite the openings 33 in the bell and whereby when the pipe 19 is supplied with gas 30 through the turning plug 5, as heretofore described, the flame will shoot out from the openings 32 and through the openings 33 in the bell and travel across to the burners 34 and ignite the same. Owing to the squared 35 portion 27 of the burner and the squared depressed portion 28 of the bell 29, the burner tip cannot be placed within the bell in any other position except that with the opening 32 opposite the openings 33, so that 40 the flash of the gas from the openings 32 will travel outwardly through the openings 33 and ignite the burners.

The bell 29, as heretofore described, has the squared portion 28 receiving the contracted lower squared portion 27 of the burner and the burner being attached to the pipe 19, it will be seen that the bell is supported by the burner. The upper end of the bell has ears or lugs 32' struck from the side 45 wall thereof and upon which is mounted the cap 33', having a downwardly extending flange 34, frictionally supported by the ears or lugs 32'. These ears form a space between the side wall of the bell and the downwardly turned flange 34 of the cap to allow 50 the proper amount of air to pass to the bell causing the proper combustion of the gas as it passes from the opening in the burner. The cap, as shown in Fig. 4 of the drawing, 55 extends over beyond the side wall of the bell and prevents any dripping from the stove entering the bell and clogging the burner and allows said drippings to drop down off of the bell.

60 65 The pipe 22, as shown in Fig. 4 of the

drawing, has its end screw-threaded as indicated at 25', and is screwed into the passage 17. The pipe within the bent portion 23 of the pipe 19 is in the form of a wave as indicated at 35 and placed within the pipe 19, 70 when the said pipe is straight. By this crimping of the pipe 22 at 35, it will be seen that when the pipe 19 is bent, as indicated at 23, the crimps allow for the extension of the pipe 22 to allow the threaded portion 35 to extend beyond so as to be screwed into the opening 17 and also allow for the portion 36 to extend within the burner 26 and be flush with the upper end thereof, as fully shown in Fig. 4 of the 80 drawings. The portion 35 and the portion 36 of the pipe 22 have to extend a predetermined distance beyond the ends of the pipe 19, so that connection can be made with the valve casing, shown in Fig. 2 of the drawings and also to have the upper end of the portion 36 of the pipe flush with the upper end of the burner 26, as fully shown in Fig. 4 of the drawings. During the bending operation of the pipe 19, the extended ends of 90 the pipe 22 are held the predetermined distance out of the pipe 19 and the material required for the bending of the pipe 19 at 23 is compensated for by the form of a wave 35. From the foregoing description, it will be 95 seen that the gas from the main supply is always passing through the passage 17 to the pipe 22 and burning from the open end 36 of the burner, thus forming a pilot light. When it is desired to ignite one of the main 100 burners the plug 5 is turned through the medium of the handle 16, which causes the passage 6 to register with the passage 7 in the valve casing for a short period of time and allows a certain amount of gas to pass 105 to the pipe 19 and the gas then passes outwardly through the openings in the burner 26 and is ignited by the pilot light and flashes outwardly through the openings in the bell 29 some distance therefrom and ignites the main burners arranged opposite 110 the openings. When the handle is released the spring 10 causes the plug 5 to turn backward to the position shown in Fig. 2 of the drawings, which allows another supply of gas to pass through the plug 5 to the pipe 19 and thus cause another flash from the lighter which would light the burners in case they had not been lighted by the first flash.

Having thus described my invention, what I claim and desire to secure by Letters Patent is:

1. A lighter of the character described, comprising a vertically disposed burner having horizontally arranged openings, a bell surrounding the burner and having horizontally arranged openings opposite the openings in the burner, a cap on the upper end of the bell and spaced therefrom, and a 120

pilot burner within the center of the main burner.

2. A lighter of the character described, comprising a burner having horizontally arranged openings, a gas supply for the burner, a pilot burner within the center of the main burner and having a gas supply leading through the supply for the burner, and a bell surrounding the burner and having horizontally arranged openings opposite the openings in the burner.

3. A lighter of the character described comprising a vertically disposed burner, having horizontally arranged openings, a gas supply for the burner, a pilot burner within the main burner at the center, a gas supply for the pilot burner extending downwardly through the main burner and through the gas supply for the main burner, and a bell surrounding the main burner and having horizontally arranged openings opposite the openings in the main burner.

4. A lighter of the character described, comprising a vertically disposed burner having horizontally arranged gas discharge openings, a gas supply pipe for the lower end of the burner, a pilot-burner within the center of the main burner, a gas supply pipe for the pilot burner extending downwardly through the main burner and through the gas supply for the main burner, a bell surrounding the main burner and having horizontally arranged openings opposite the openings in the main burner, and a removable cap carried by the bell and spaced therefrom and extending out beyond the vertical walls thereof, substantially as shown and described.

5. A lighter of the character described, comprising a vertically disposed burner having horizontally arranged openings, a bell surrounding the burner and having horizontally arranged openings opposite the openings in the burner, a gas supply pipe for the burner, a valve within the gas supply for controlling the same, and means carried by the valve for allowing two charges of gas to pass to the burner during a single operation of the valve.

6. A lighter of the character described, comprising a vertically disposed burner having horizontally arranged openings, a bell surrounding the opening and having horizontally arranged openings opposite the openings in the burner, a gas supply in the burner, a spring pressed turning plug within the gas supply and adapted to allow two charges of gas to pass to the burner during a single operation of the valve.

7. A lighter of the character described, comprising a burner having horizontally arranged gas discharge opening, a bell surrounding the burner and having horizontally arranged openings opposite the openings in the burner, a gas supply for the

burner, a turning plug within the gas supply and normally held closed by a spring and constructed and arranged to allow two charges of gas to pass to the burner during a single operation of the turning plug.

8. A lighter of the character described comprising a vertically disposed burner having horizontally arranged openings adjacent its upper end and a squared portion below said openings, a bell surrounding the burner and having horizontally arranged openings opposite the openings in the burner, said bell having a squared depressed lower end receiving the squared portion of the burner whereby the openings in the burner register with the openings in the bell, and a gas supply pipe communicating with the burner.

9. A lighter of the character described comprising a vertically disposed burner having horizontally arranged openings in its upper end, a squared flange carried by the burner below the openings, a bell surrounding the burner and having horizontally arranged openings opposite the openings in the burner, said bell having a squared depressed lower end receiving the squared portion of the burner, and a nut on the burner below the squared portion of the bell, whereby the burner is secured within the bell with its openings registering with the openings in the bell, and a gas supply pipe communicating with the burner.

10. A lighter of the character described, comprising a vertically disposed burner having horizontally arranged gas openings, a bell surrounding the burner and having openings registering with the openings in the burner, a gas supply pipe for the burner, a valve casing in communication with the gas supply, a turning plug in said casing having a transverse opening adapted to allow the gas to pass to the supply pipe, and a spring normally holding the turning plug closed whereby the opening of the turning plug allows a charge of gas to pass to the supply pipe and when released the spring closes the valve and allows a second charge to pass to the gas supply pipe of the burner.

11. A lighter of the character described, comprising a burner, a bell surrounding the burner, and having horizontally arranged openings, a gas supply for the burner, a valve casing connected to the end of the gas supply pipe, a turning plug having an opening to allow the gas to pass to the gas supply pipe, spring pressed means for normally holding the valve closed, and a valve within the casing between the turning plug and gas supply pipe for giving a normal supply of gas to the gas supply pipe.

12. A lighter of the character described, comprising a vertically disposed burner having horizontally arranged openings, a bell surrounding the burner and having hori-

- zontally arranged openings registering with the openings in the burner, a gas supply for the lower end of the burner, a pilot burner within the upper end of the main burner, a 5 gas supply pipe connected to the pilot burner and extending downwardly through the gas supply of the main burner, and a valve carried by the end of the gas supply and constructed and arranged to allow a constant 10 flow of gas to the pilot burner through the pipe within the main supply pipe.
13. A lighter of the character described, comprising a vertically disposed burner having horizontally arranged openings, a bell 15 surrounding the burner and having horizontally arranged openings registering with the openings in the burner, a gas supply pipe for the lower end of the burner, a pilot light in the upper end of the main burner, 20 a gas supply pipe for the said pilot light extending downwardly through the main supply pipe, a valve carried by the end of the gas supply pipe and adapted to control the gas to the main burner and having a bypass 25 in communication with the pipe within the burner and the main supply pipe, and maintaining a constant supply of gas to the pilot burner.
14. A lighter of the character described, 30 comprising a vertically disposed burner having horizontally arranged openings, a bell surrounding the burner and having horizontally arranged openings registering with the openings in the burner, means for supplying 35 the burner with gas, a pilot light within the upper end of the main burner, means for maintaining a constant supply of gas to the pilot burner, the upper end of the bell having outwardly pressed ears, and a cap frictionally supported by the ears, whereby a 40 space is left around the upper end of the bell for supplying air, substantially as shown and described.
15. A lighter of the character described, 45 comprising a vertically disposed burner having horizontally arranged openings, a bell surrounding the burner and having horizontally arranged openings opposite the openings in the burner, a gas supply for the 50 lower end of the burner, a pilot burner within the upper end of the burner and a supply pipe for the pilot light extending downwardly through the burner and through the gas supply for the main burner.
16. A lighter of the character described, 55 comprising a vertically disposed burner having horizontally arranged openings, a bell surrounding the burner and having horizontally arranged openings opposite the openings in the burner, a pilot light within the 60 center of the upper end of the burner, a gas supply for the main burner, a gas supply for the pilot burner and extending downwardly through the main gas supply, a valve connected to the main supply and adapted to 65 control the gas thereto, a screw valve for regulating the supply of gas supplied by the valve, means for supplying the pilot light with gas, and a screw valve for regulating the constant supply of gas to the pilot burner.
20. The combination with a plurality of burners, of a lighter therefor comprising a vertically disposed burner having horizontally arranged openings in radial alinement with the burner, a bell surrounding the burner and having horizontally arranged openings in alinement with the openings in the burner, and said burner and bell constructed and arranged so that they cannot be secured together without the openings in the bell and burner registering.
21. In combination with a plurality of 125 burners, of a lighter located between the burner and comprising a vertically disposed burner having horizontally arranged openings extending in a radial alinement with the burner, a bell constructed and arranged 130
- control the gas thereto, a screw valve for regulating the supply of gas supplied by the valve, said valve having a bypass communicating with the pipe supplying the gas to the pilot burner, and a screw valve in said bypass for the purpose of regulating the pressure of the gas to the pilot-burner.
17. In combination with a plurality of 75 burners, of a lighter therefor comprising a vertically disposed burner having horizontally arranged openings in radial alinement with the burner, a bell surrounding the burner and having horizontally arranged openings in alinement with the openings in the burner, and means carried by the bell for securing the burner in the bell whereby the burner cannot be positioned with its openings out of alinement with the openings in the bell.
18. In combination with a plurality of 85 burners, of a lighter located between the burner and comprising a vertically disposed burner having horizontally arranged openings extending in a radial alinement with the burner, a bell constructed and arranged 90 to at all times maintain its relative position with the burner and having horizontally arranged openings in alinement with the openings in the burner, whereby it is impossible for the openings in the bell and the burner 95 to get out of alinement, substantially as shown and described.
19. A lighter of the character described, 100 comprising a vertically disposed burner having horizontally arranged openings, a bell surrounding the burner and having horizontally arranged openings opposite the openings in the burner, a pilot-light within the center of the upper end of the burner, a gas supply for the main burner, a gas supply for 105 the pilot-light and extending through the main burner supply pipe, a valve connected to the main supply and adapted to control the gas thereto, a screw valve for regulating 110 the supply of gas supplied by the valve, means for supplying the pilot light with gas, and a screw valve for regulating the constant supply of gas to the pilot burner.

to at all times maintain its relative position with the burner and having horizontally arranged openings in alinement with the openings in the burner, whereby it is impossible 5 for the openings in the bell and the burner to get out of alinement, substantially as shown and described.

22. A lighter of the character described, comprising a vertically disposed main 10 burner, a pilot burner within the center of the main burner, a gas supply pipe for the main burner, a gas supply for the pilot burner and extending through the main gas supply pipe and having a waved portion 15 within the said main supply pipe and a valve carried by the end of the main supply pipe constructed as shown and described.

23. A lighter of the character described, comprising a main burner, a pilot within the 20 center of the main burner, a gas supply for the main burner, a gas supply for the pilot burner and extending through the main gas supply pipe and having a waved portion within the main supply pipe, a valve having 25 a screw-threaded connection with the main supply pipe and the pilot supply pipe constructed and arranged to allow a constant flow of gas to the pilot supply pipe, substantially as shown and described.

30 24. A burner of the character described, comprising a main burner having an open upper end, a gas supply pipe connected to the lower end of the burner, a second gas supply pipe extending therethrough and 35 through the burner and having its end filling the open upper end of the main burner to form a pilot light, said pipe having a waved portion within the main gas supply pipe, a valve into which the main supply 40 pipe and the pilot supply pipe is adapted to screw and having separate passages, and a turning plug within the passage supplying the main supply pipe with gas whereby the pilot light supply pipe has a constant supply 45 of gas and the main burner supply is controlled by a valve, substantially as shown and described.

25. A lighter of the character described, comprising a burner having horizontally arranged opening and a central opening at its 50 upper end, a gas supply connected to the lower end of the burner, a small pipe extending through the main gas supply pipe and through the burner and fitting within the 55 open upper end of the burner and forming a pilot light, said small pipe having a waved portion within the main supply pipe, a valve casing having a screw threaded portion adapted to receive the opposite end of the 60 main gas supply pipe and having a straight passage therethrough adapted to receive the pilot light supply pipe which is screwed therein, a screw valve controlling the said

passage, said casing having a bypass communicating with the main supply pipe, a 65 needle valve in said bypass and a turning plug in said bypass whereby the main supply is controlled by the turning plug and a constant flow of gas fed to the pilot light supply pipe. 70

26. A lighter of the character described comprising a vertically disposed burner having horizontally arranged gas openings, a bell surrounding the burner and having openings registering with the openings in 75 the burner, a gas supply pipe for the burner, a valve casing in communication with the gas supply, a pilot burner within the main burner, a gas supply for the pilot burner and extending through the gas supply for the main burner, a turning plug in the gas supply for the main burner, and a bypass extending around the turning plug for supplying gas to the pilot burner. 80

27. A lighter of the character described, comprising a main burner, a pilot within the center of the main burner, a gas supply for the main burner and having a downwardly curved portion adjacent the burner, a gas supply for the pilot burner and extending 90 through the main gas supply pipe and having a waved portion within the compound curved portion of the main supply pipe, a valve having a screw-threaded connection with the main supply pipe and the pilot supply pipe and constructed and arranged to allow a constant flow of gas to the pilot supply, substantially as shown and described. 95

28. A burner of the character described, comprising a main burner having horizontally arranged openings and a central opening at its upper end, a gas supply connected to the lower end of the burner and having a downwardly curved portion, a small pipe extending through the main gas supply pipe 105 and through the burner and fitting within the upper open end of the main burner and forming a pilot burner, said small pipe having a waved portion within the compound curved portion of the main supply pipe, a 110 valve casing having a screw-threaded portion adapted to receive the opposite end of the main gas supply pipe and having a straight passage therethrough adapted to receive the pilot light supply pipe which is 115 screwed therein and a turning plug adapted to control the supply of gas to the main supply pipe to allow a constant flow of gas to the pilot light supply pipe.

In testimony whereof I have reurnt, affi. my 120 signature in the presence of two witnesses.

FRED G. NICOLAUS.
